(57) **CLAIM**

The ornamental design for an apparatus for handling goods, as shown and described.

DESCRIPTION

FIG. 1 is a front view of an apparatus for handling goods, showing my new design;

FIG. 2 is a back view thereof;

FIG. 3 is a right view thereof;

FIG. 4 is a left view thereof;

FIG. 5 is a top view thereof;

FIG. 6 is a bottom view thereof;

FIG. 7 is a top, front, and right side perspective view thereof; and,

FIG. 8 is a top, front, and left side perspective view thereof.

The broken lines in the drawings depict portions of the apparatus for handling goods that form no part of the claimed design.
